UNITED STATES PATENT OFFICE.

D. W. WYMAN, OF NEW YORK, N. Y.

IMPROVEMENT IN LOCOMOTIVE-ENGINE FURNACES.

Specification forming part of Letters Patent No. **89,261**, dated April 20, 1869.

To all whom it may concern:

Be it known that I, D. W. WYMAN, of the city, county, and State of New York, have invented a new and useful Improvement in Ash-Pans for Locomotive-Engines, of which the following is a full, clear, and exact description, reference being had to the accompanying drawing, forming part of this specification, and in which—

Figure 1 represents a plan of an ash-pan constructed in accordance with my improvement; Fig. 2, a side or edge view of the same; and Figs. 3 and 4, central vertical sections thereof, taken at right angles to each other.

Similar letters of reference indicate corresponding parts.

This invention consists, first, in a novel arrangement of side-draft flues or passages and dampers, or valves thereto, in combination with a deflecting flange or flanges arranged to project internally from the sides of the pan at its top or upper portion, whereby not only is the air admitted through the sides of the pan above the basin or bottom portion thereof, but the dampers or valves and air flues or passages controlled by them are secured from being clogged or choked by snow on the track, and the incoming air heated in its way to the fire by its contact with and radiation from the deflecting flange or flanges, which are exposed on its or their upper surface or surfaces to the action of the fire in the fire-box; secondly, the invention includes a novel combination and arrangement of levers, cranks, and link-rods for operating the several dampers or valves which control the air flues or passages in the sides of the ash-pan.

Referring to the accompanying drawing, A² is an ash-pan of rectangular form, the upper portion of the sides of which is provided with air flues or passages a² a², that are controlled by dampers or valves b² b², which are here shown as being of a hinged character or action, and arranged so as to open inward, there being a valve or damper and air flue or passage to each of the four sides of the pan. B² B² is a curved or downwardly-sloping flange, arranged to project internally from the upper portion of the pan above, and so as to face the flues a² a², with a sufficient space between said flange and the sides of the pan, around each of which such flange is extended to ad-

mit of the play of the valves b² b² beneath it, and to form a channel or passage for the incoming air and proper distribution of the same to or over the fire. Thus arranged, this plate or flange not only serves to deflect and direct down toward the base portion of the ash-pan the incoming air as it is admitted through the upper portion of said pan at its sides, but said plate or flange, being exposed on its upper surface to the action of the fire, serves to heat the incoming air, which promotes combustion.

By the arrangement of two of the air-flues a² a² and dampers b² b² in the upper portion of the pan at its sides, the same are secured from being clogged or interfered with by snow on the track, while the deflecting flange B² B² serves to give all the advantage as regards feed of the air to the fire of a lower admission.

The swinging dampers or valves b² b² on the several sides of the pan are operated simultaneously by means of T-shaped levers D² D², working on fulcrum-pins c² c², arranged on two of the adjacent sides of the pan, said levers being suitably connected by a lifting-rod to work them in unison. Pivoted to the shorter arms of these levers are link-rods d² d², that connect at their opposite ends with cranks or arms e² e², fast to the fulcrum-shafts f² f² of the dampers b² b², which combination secures the joint action of the opposite dampers, and, by uniting the two levers D² D² to operate in unison, of the several dampers on or to all the sides of the pan.

The T-shaped levers D² D² on the two adjacent sides of the pan should be so arranged as that their longer arms, if extended, would intersect each other, whereby they may be readily connected to work in unison, and by one and the same rod.

The lower or what may be termed "basin" portion of the pan is of a corrugated character, being for the most part made up of double inclined hollow ribs E² E², arranged to extend across the bottom of the pan diagonally, or from corner to corner, thus giving a solid center to the pan and materially strengthening it, while the sloping sides of said ribs or corrugations serve to direct the ashes or cinders to discharge-openings g² g² made in the bottom of the pan, said openings being closed, when it is not required to dump or discharge, by a plate or disk, F², turning on a center, as at h²,

and operated by a handle, i^2 , which disk has openings g^4 g^4 in it for, by suitably turning it, establishing communication with the openings g^2 g^2 to effect discharge of the ashes or cinders.

What is here claimed, and desired to be secured by Letters Patent, is—

1. The arrangement of the side flues, a^2 a^2 , and dampers b^2 b^2 , controlling the same, in combination with the interior upper deflecting flange or flanges B^2 B^2 , arranged relatively to said flues and lower or base portion of the pan, substantially as specified.

2. The arrangement of the T-shaped levers D^2 D^2 , link-rods d^2 d^2 , and cranks e^2 e^2 on adjacent sides of the pan, for operating the several valves or dampers b^2 b^2 , substantially as shown and described.

D. W. WYMAN.
